S. J. ORNSTON.

STRAP SEAL.

APPLICATION FILED SEPT. 10, 1919.

1,345,806.

Patented July 6, 1920.

Inventor

SIDNEY J. ORNSTON,
By his Attorney

Geo. F. Heath

UNITED STATES PATENT OFFICE.

SIDNEY J. ORNSTON, OF NEW YORK, N. Y.

STRAP-SEAL.

1,345,806.

Specification of Letters Patent.

Patented July 6, 1920.

Application filed September 10, 1919. Serial No. 322,809.

To all whom it may concern:

Be it known that I, SIDNEY J. ORNSTON, a citizen of the United States, and a resident of the borough of Manhattan, city, 5 county, and State of New York, have invented certain new and useful Improvements in Strap-Seals, of which the following is a specification.

My improvements relate to metallic tie 10 pieces used for securing together the ends of metallic binding straps after the latter have been drawn taut by any of the various mechanical expedients known in the art. The object of my invention is to afford a 15 simple, cheap, but effective and positive coupling seal of this character which is practically safe and reliable in the sense that it cannot be tampered with or opened up without damaging the seal to such an extent as 20 to preclude the possibility of its being successfully readjusted or closed,—while at the same time the operation of clenching the seal interlocks and unites its plies integrally with the inclosed overlapping portions of 25 the binding strap in such manner as to resist all tensile strain and render the seal as strong as, if not stronger than, the band itself.

Hence my invention consists in the specific 30 construction and arrangement of parts described and claimed, distinctive features being the formation of the body of the coupling piece with superposed under plies or laps of full width, and in alinement with 35 the strap end sleeve or receptacle, so that the edges of the said superposed under plies extend transversely across the strap ends when the latter are inserted in said receptacle, and in the closing of the otherwise open 40 edges of the coupling piece and securing the said under-ply laps by means of over and inwardly turned flanges integral with the top or middle portion of the one piece blank from which the whole coupling sleeve 45 is formed,—the edges of said lateral flanges being thus positioned on the under side of the seal and against the package when applied thereto, so that the several thicknesses of metal composing the seal cannot be tampered with or pried apart under ordinary 50 conditions of use without obviously destroying the coupling seal.

In the accompanying drawings,

Figure 1, is a view of my seal blank, fully 55 extended;

Fig. 2, is a view of the same with one of

the laps folded over the central portion of the blank, said central portion constituting the upper plate or face of the seal;

Fig. 3, is a view showing the other lap 60 folded into position to constitute the bottom plate of the device;

Fig. 4, is a view showing the completion of the coupling device by the folding of the lateral edge flanges of the central face plate 65 over and under the lateral edges of the flap plates,—this view representing the under side of my coupling seal;

Fig. 5, is a view of the upper or face side 70 of my coupling seal;

Fig. 6, is a section taken upon plane of line 6—6, Fig. 4;

Fig. 7, is a section taken upon plane of line 7—7, Fig. 4;

Fig. 8, is a top view of my coupling seal 75 applied to the overlapping ends of a flat metallic band;

Fig. 9, is an edge view of the parts shown in Fig. 8;

Fig. 10, is a view of the under side of the 80 parts shown in Fig. 8;

Fig. 11, is a view like unto Fig. 8, after the parts have been clenched together;

Fig. 12, is a section taken upon plane of line 12—12, Fig. 11, only the coupling sleeve 85 being section lined however, to obviate confusion in hatching.

In this connection it may be stated that the thickness of the metal of which my coupling seal is formed, as well as of the strap 90 ends, is necessarily exaggerated in certain figures of the drawings for the sake of clearness of illustration. As a matter of fact the material may be and is less than one half the thickness of that shown, although 95 I do not limit myself in this respect.

My improved coupling seal for metallic bands is formed from a blank consisting of a single piece of sheet metal of suitable character and thickness, and of a configuration substantially like that shown in Fig. 1. That is to say, the blank has a central portion a , which constitutes the outer or upper plate of the device when folded ready for use,—said central portion a , having longitudinal extensions a' , a'' , beyond the transverse strap slots a^* , and also having lateral flange extensions a^3 .

The longitudinal extensions or laps a' , a'' , are folded over each other to form the bottom or under side of the sleeve or receptacle for the ends s , s , of the metallic strap,—the

space between the inner side of the face plate a , and the opposed surface of the inner lap (a' , as shown in the drawings, although either lap a' , a^2 , may be so positioned) being sufficient to accommodate the overlapping strap ends as passed through the slots a^x , a^x . After the longitudinal extensions or laps a' , a^2 , are thus folded the one over the other, as in Fig. 3, the lateral flange 10 extensions a^3 , a^3 , of the face plate a , are bent around the side edges of said laps a' , a^2 , the edges of said flanges a^3 , a^3 , being permanently positioned underneath and against the lower plate. Thus the said 15 lateral flanges a^3 , a^3 , not only isolate and protect the side edges of the lap plates a' , a^2 , but also sustain and reinforce said bottom plates, and bind the parts of the blank into a stiff unitary structure. Not the least 20 important function afforded by the lateral flanges a^3 , a^3 , thus utilized, is their prevention of the insertion of a sharp point or blade between the superposed plates of the seal, so that my coupling device cannot be 25 pried apart or otherwise tampered with surreptitiously.

The completed coupling is shown in Figs. 4, 5, 6 and 7, of the drawings, in which shape it is ready to receive and embrace the 30 ends of the strap as shown in Figs. 8, 9 and 10. When thus positioned upon the overlapping strap ends s , s , the seal is completed and rendered permanent by puncturing the face plate a , and the underlying portions 35 of the strap, and preferably by punching through all the superposed thicknesses of metal, as indicated in Figs. 11 and 12. By this means the affected portions of the straps are bent over and clenched by and 40 against adjacent parts of the coupling device, and a positive seal is attained which will effectually resist tensional strain, and which can only be rendered inoperative by the actual rupture of the parts.

When the blank is folded, ready for use, 45 the slots a^x , a^x are at the margins of opposite edges of the coupling, confined between shoulders formed by the walls of the slots, as seen best in Figs. 8, 10 and 11, while the lap plates a' , a^2 overlap each other the full 50 width of the coupling, and then the flanges a^3 , a^3 are folded over the overlapped portions, as seen in Fig. 7. When the parts are punched, as seen in Fig. 12, the parts are so firmly held together that separation can- 55 not take place.

What I claim as my invention and desire to secure by Letters Patent is,

1. A strap seal of the character designated, comprising the overlapping strap 60 ends, and an embracing coupling consisting of a single blank of sheet metal formed with a central outer face plate, strap slots in said blank, and overlapping end extensions, and lateral extensions at opposite edges and 65 foldable toward each other over the oppositely-folded portions of the seal to protect the edges thereof, the straps and superposed coupling plates being punctured to clench the parts together, for the purpose de- 70 scribed.

2. A strap seal of the character designated, comprising the overlapping strap ends, and an embracing coupling consisting of a single blank of sheet metal formed with 75 a central outer portion or face plate, strap slots, and overlapping end extensions in close contact with each other, the lateral edges of said central outer portion or face plate being bent around and under the said 80 overlapping end extensions of the blank, and the straps and superposed plates of the coupling being punctured to clench the parts together, for the purpose described.

SIDNEY J. ORNSTON.
